UNITED STATES PATENT OFFICE.

ALCIBIADE A. BRODEUR, OF WORCESTER, MASSACHUSETTS.

DESIGN FOR A CASING FOR MUSCLE-TESTING MACHINES.

No. 39,159.

Specification for Design.

Patented Feb. 25, 1908.

Application filed December 14, 1907. Serial No. 406,568. Term of patent 7 years.

To all whom it may concern:

Be it known that I, ALCIBIADE A. BRODEUR, a citizen of the United States, residing at Worcester, in the county of Worcester and State of Massachusetts, have invented a new, original, and ornamental Design for a Casing for Muscle-Testing Machines, of which the following is a specification, reference being had to the accompanying drawing, forming part thereof.

The figure is a perspective view of a casing for a muscle testing machine showing my new design.

I claim:

The ornamental design for a casing for muscle testing machines, as shown.

ALCIBIADE A. BRODEUR.
